UNITED STATES PATENT OFFICE.

FRANCIS A. BATES, OF PHILADELPHIA, PENNSYLVANIA, ASSIGNOR TO THE MORSE, WILLIAMS & COMPANY, OF PENNSYLVANIA.

DESIGN FOR A CYLINDER-HEAD FOR HOISTING-MACHINES.

SPECIFICATION forming part of Design No. 26,073, dated September 22, 1896.

Application filed May 23, 1896. Serial No. 592,882. Term of patent 7 years.

To all whom it may concern:

Be it known that I, FRANCIS A. BATES, of the city and county of Philadelphia, State of Pennsylvania, have invented and produced 5 a new and original Design for Front Cylinder-Heads of Hoisting-Machines, of which the following is a specification.

My design is shown in the accompanying drawings, in which—

- 10 Figure 1 is a front elevation of the cylinder-head. Fig. 2 is a plan view of the same, and Fig. 3 is a side elevation.
- 15 The head consists of a frame A of more or less circular form, having supporting-feet B and outwardly-projecting arms C C springing from the sides of the frame A. These arms C C are wide where they spring from the frame A and taper toward the ends, where they terminate in recessed extremities D D.
- 20 The frame A embraces the annular flange

E and the central portion F, bulging forward and forming a hollow space open at the rear. An opening G, through one of the arms C, extends into this hollow space on the frame A. Fins H spring from the flange E at the top, 25 one on each side, but a single fin may be substituted, or they may, if desired, be entirely omitted.

What I claim as new, and desire to secure by Letters Patent, is—

The design for a cylinder-head for hoisting-machinery &c. substantially as herein described and shown.

In testimony of which invention I have hereunto set my hand.

F. A. BATES.
